E. P. GAINES.

Millstone Dress.

No. 7,980.

Patented March 4, 1851.

Inventor
Edward P. Gaines

UNITED STATES PATENT OFFICE.

E. P. GAINES, OF MELROSE, TEXAS.

DRESSING MILLSTONES.

Specification of Letters Patent No. 7,980, dated March 4, 1851.

To all whom it may concern:

Be it known that I, EDMUND P. GAINES, of the county of Nacogdoches and State of Texas, have invented a new and improved 5 mode of dressing millstones used for the purpose of grinding every kind of grain into meal flour &c., &c., and I do hereby declare that the following is a full and exact description thereof, reference being had to 10 the accompanying drawings and to the letters of reference marked thereon.

To enable others skilled in the art to make and use my invention, I will proceed to describe its construction and operation.

15 I take the upper and lower mill stone which I intend to operate upon and grind the faces that are to be dressed perfectly smooth and even, the object being to make each of these faces abut. In geometry, it is 20 termed a plane. This is done by grinding sand and water through them until their faces assume this shape. By use of dividers, &c., I (by diameters or straight lines drawn through the center and terminating in the 25 circumference on each side) divide the face into equal parts. (In this instance the model from which the drawing is taken being a small one I divided the face into only eight parts.) The number of these varies with the 30 diameter of the plane. The stones having the largest diameters may be divided into as many as eighteen equal parts.

I then make a curved rule as represented 35 in the drawing by which the work upon the face of the stone is laid off or measured. The concave side of this rule must in every instance have the same curvature as the circumference of the stone, the face of which you intend to measure by it. Or in other 40 words the mill stone and this curve must, in all cases, have the same or an equal radius. This rule is made just long enough to reach from the circumference to the eye of the stone in measuring it. In making measure- 45 ments the broadest end of this rule is always placed at the circumference and the other at, or toward, the eye. At the circumference this rule is about one eighth part broader than it is at the eye and it gradually 50 becomes smaller from the one end to the other. The convex and concave sides of the rule have the same curvature; or in other words their radius is the same. The broadest ends of these rules vary from one inch to two 55 inches and a quarter wide. Their size is

large or small in proportion to that of the diameter of the stone to be dressed.

The principal or master furrows (for I so designate them) on the face of the stone are laid off and made thus. For example 60 upon the diameter *a a'* place the letter *a* upon the rule on the letter *a* at the circumference, and *b* upon the rule on *b* at the eye, and mark off the size and figure or shape of the rule upon the stone. This is to 65 be the size of the furrow and its shape. You then cut your furrow on the convex side or line of the rule from one quarter of an inch to an inch in depth. The depth of this is in proportion to the diameter of the 70 stone. The furrow along the line of this convex side is almost perpendicular. The furrow however is a little narrower than it would be, if this side were entirely perpendicular. From the lowest part of this 75 furrow (along the whole of its length) to the line on the surface drawn upon the concave side of the rule, the furrow has the same curvature as the rule itself. This furrow is deeper by about one eighth part 80 at the circumference than it is at the eye; its depth as you pass toward the eye, becoming gradually less. A furrow is to be made in the same way on each one of the aforesaid eight times or more as the size 85 of the diameter of the stone may require. And generally there are to be as many master furrows as there are parts into which the stone is divided; and one of 90 these must be made as described above on each of the lines dividing it. A small portion of the hollow of each of these furrows is cut out at the eye in order that they may be enabled better to receive the grain.

After you have completed those, then take 95 your rule and place its concave side on the concave line of the master furrow and mark off its size upon the surface. Then place the concave side of the rule on the line which convex line of the master furrow and mark 100 off its size again upon the stone (it will be found that the end of this, next to the eye, will pull upon a master furrow). Upon the size of the rule marked off last you next make a furrow on the plan upon which 105 you made the others. This is called a short furrow. The end of this, next to the eye, will not be exactly like a master furrow was made, for it will there intersect one of them. But the object is to make it as near like 110

the first as it can be made. The lower edge of this furrow is continued on to the lower or back edge of the master furrow. The rest of them are laid off and made in the 5 same way.

Upon the smooth surface (of the size of the rule) which is now left between each master and short furrow you must cut small grooves, from seven to twelve in number, 10 (corresponding to the size of the rule). These are to run from the circumference to the eye of the stone. They are to be from one sixteenth to one eighth of an inch deep (their depth to be in direct proportion to 15 the diameter of the stone); and they are to be as nearly parallel as they can be made to the curved edges of the rule. On the equal number of triangular surfaces, which will be now left, you must cut one groove 20 along the line which is next to the edge of the master furrow, so as to preserve that edge. And then you must cut one through the center of the triangle, so as to run from its acute angle to the middle of its circumference. Then cut grooves like those above 25 on each side of this and parallel to it, until they cover the whole of the triangle. Before these grooves are cut they are laid off by the curve of the rule. You, of course, 30 dress each of these triangles precisely in the same way. When you may wish to dress, on this plan, stones that have been dressed on any other, you in the first place render their faces smooth and even in the 35 manner directed above.

The annexed drawing and description given above is supposed to be the bed or bottom stone of the mill. The upper stone or runner is made precisely in the same 40 way. But it is easily seen that when this top stone is inverted and placed upon the lower one, the curvature of its lines will be reversed. When the mill is running, the 45 convex curves of the upper stone or runner are in front.

It will be seen that about one-half of each master furrow next to the eye is behind the diameter upon which it is made. The reverse of this is true in relation to the 50 other half situated next to the circumference. It will be also seen that the short furrow has, next to the circumference, double the draft or inclination of the master furrow. These furrows are so constructed

as to retain nearly all of the grain near to 55 the eye or centre of the stone, until it is ground into meal or flour. Mills dressed upon other plans grind the grain nearer to their circumferences. This, upon the principle of the common lines, gives them much 60 greater resistance when grinding, than are to be overcome upon the plan here proposed. On this plan the furrows receive the grain and make it into hominy or small particles so the face can receive it and grind it 65 into meal. In other plans the stones are made hollow on the entire surface near the eye (which by millers is termed the bosom) and this receives the grain and passes it off toward the circumference where it is 70 ground.

Each one of the grooves described above shears or cuts an equal quantity of grain to that sheared or cut by the curved edge of a furrow. This as numerous experiments 75 prove, enables the plan proposed, with an equal power, to grind, in a given time, say three or four times the amount of grain, that can be ground upon any other plan now in use. The grooves, which are used 80 in no other plan) separates the bran from the meal or flour much more effectually and with much more ease to the machine than is done upon any other plan and the yield is consequently greater than in any 85 other.

Mills dressed in this manner can not be crowded or choked, hence it has no such limit to the quantity it can grind, in a given time as, from this cause, other mills 90 have which are differently dressed. And it is believed that large stones dressed on this plan, and having a sufficient power to move them, might grind one hundred bushels in one hour. The shape and depth of the furrows and the principle of the drawing are 95 such that the mill dressed in this plan will avoid heating the flour however long you may continue to run it.

What I claim as my invention and desire 100 to secure by Letters Patent is—

The new and improved mode of dressing mill-stones which I have described above as fully and correctly as I can.

E. P. GAINES.
